UNITED STATES PATENT OFFICE.

JOHN W. COOMBS, OF MOUNT VERNON, NEW YORK.

IMPROVEMENT IN COAL-SCUTTLES.

Specification forming part of Letters Patent No. 35,436, dated June 3, 1862.

To all whom it may concern:

Be it known that I, JOHN W. COOMBS, of Mount Vernon, county of Westchester, and State of New York, have invented a new and Improved Coal-Scuttle; and I do hereby declare that the following is a full, clear, and exact description of the same, reference being had to the accompanying drawings, forming a part of this specification, in which—

Figure 1 represents a side elevation of my invention. Fig. 2 is a longitudinal vertical section of the same, the line $x x$, Fig. 4, indicating the plane of section. Fig. 3 is a horizontal section of the same, taken on the plane indicated by the line $y y$ in Fig. 2. Fig. 4 is a plan or top view of the same.

Similar letters of reference in the several views indicate corresponding parts.

This invention consists in the arrangement of a movable sieve in the interior of a coal-scuttle, in combination with an ash or dirt box hinged to the bottom of said scuttle in such a manner that by the action of said sieve the good coal can be separated from the dirt or ashes that may be mixed with it, and that the moisture which generally adheres to coal, and which causes coal-scuttles to rust through and wear out in a short time, is permitted to pass through said sieve down into the ash-box without injurious influence on the sides of the scuttle.

It consists, further, in the arrangement on the top edge of the scuttle of spring-ears with two sockets, one to receive the bail and the other the pivot of the hinged lid, in such a manner that the lid can be easily taken off for the purpose of packing the scuttles, so that the cost of manufacturing them is not materially increased.

It consists, also, in the employment of a hinged movable lid attached to the top edge of the scuttle in such a manner that the coal from the interior of said scuttle can pass out without obstructions, and that the dust which may arise during the operation of sifting is retained in the interior of the scuttle.

To enable those skilled in the art to make and use my invention, I will proceed to describe its construction and operation with reference to the drawings.

The scuttle A is made in the usual form and manner, of sheet metal, and is provided with a bail, B, and a lid, C. This lid is made of

two parts, $c d$, which are connected by a hinge-joint, a ; and it is provided with a flange, b , which catches over the edge of the scuttle, as clearly shown in Figs. 1 and 2. The flange on the rear part, c , of the lid is so arranged that it hugs the edge of the scuttle tightly, whereas the front part closes down easily, so that by tilting the scuttle the coals which may be contained in the same force open the lid and pass out without obstruction. The pivot e of the hinge-joint a is retained by two ears or lugs, f , that are firmly attached to the sides of the scuttle. Each of these lugs is provided with two holes or sockets, g , one to receive the pivot e , as previously stated, and the other to receive the ends of the bail B , and said lugs are so arranged that they can be sprung apart sufficiently far to release the ends of the pivot e , so that the lid can be removed without difficulty.

When a number of scuttles are to be packed for transportation, it is essential to be able to remove the lids; in fact, it would be impossible to manufacture my scuttle on an extensive scale if the lid could not be removed, for it is obvious that if the scuttles could not be packed one inside the other they would be so bulky that they could not be transported sufficiently convenient to render their manufacture practicable. By the use of spring-ears with two sockets this object is attained in a simple and effective manner without materially increasing the cost of the scuttle.

D is the sieve, which is placed loosely on a metal ring, h , that is secured in the interior of the scuttle by means of screws i . These screws project over the edge of the sieve, as clearly shown in Fig. 3, so that they prevent the same from coming out spontaneously, leaving it free, however, to rotate in the ring in either direction. Said sieve is provided with a handle, j , which passes through a recess in the vertical edge of the ring h and through a slot, k , in the side of the scuttle, and which serves to impart to the sieve a vibrating motion for the purpose of separating the dirt or ashes from the good coal. All those parts which pass through sieve collect in the ash-box E, which is connected to the scuttle by a hinge, l , and locked by a spring-catch, m . The hinge l is provided with a ring or handle, n , which serves to tilt the scuttle when it is desired to pour out the contents of the same, and it (the hinge) is

so arranged that the ash-box, when unlocked, drops down to the position shown in red outlines in Fig. 1, and that said ash-box can be turned over and emptied without tilting the scuttle.

The spring-catch *m* is secured to the side of the scuttle opposite the hinge *l*, and it catches into a cavity in the ash-box, as clearly shown in Fig. 2. It is so formed that it can be easily pulled out when it is desired to unlock the ash-box. The ash-box is supported by small legs *o* of any convenient form and size.

By combining a sieve and ash-box with the scuttle the moisture adhering to fresh coals is permitted to pass down into the ash-box without injury to the sides of the scuttle, and the dirt or dust is readily separated from the good coals; and, furthermore, my scuttle can be used as an ash-sifter with equal convenience and effect as the best ash-sifter now in the market.

Having thus fully described my invention, what I claim as new, and desire to secure by Letters Patent, is—

1. The combination of the scuttle *A*, hinged ash-box *E*, shaking-sieve *D*, and handle *j*, all constructed, arranged, and operating in the manner and for the purposes set forth.

2. The combination, with the sieve *D* and scuttle *A*, of the ring *h*, as and for the purpose specified.

3. The arrangement of the jointed removable lid *C*, in combination with the scuttle *A*, as and for the purpose described.

4. The combination, with the hinged lid *C* and bail *B*, of spring-ears *f*, each provided with two sockets, *g g*, as and for the purposes specified.

JOHN W. COOMBS.
